UNITED STATES PATENT OFFICE.

CHARLES F. SPERRY, OF CHICAGO, ILLINOIS

RADIATOR.

1,216,509.

Specification of Letters Patent. Patented Feb. 20, 1917.

Application filed April 28, 1916. Serial No. 94,102.

To all whom it may concern:

Be it known that I, CHARLES F. SPERRY, a citizen of the United States, and a resident of the city of Chicago, in the county of Cook and State of Illinois, have invented a certain new and useful Improvement in Radiators; and I do hereby declare that the following description of my said invention, taken in connection with the accompanying sheet of drawing, forms a full, clear, and exact specification, which will enable others skilled in the art to which it appertains to make and use the same.

My invention relates generally to improvements in radiators; and it consists, essentially, in the novel and peculiar combination of parts and details of construction, as hereinafter first fully set forth and described and then pointed out in the claims.

This invention belongs to the cellular type of radiators for cooling the circulating water of internal combustion engines. Like others of its type, the cooling section proper of this invention is built up of a plurality of duplicate units; and its novelty resides in means providing for large water and air spaces; in preventing the clogging of the water passages, and at the same time in effecting economy of material and labor in the fabrication of the same. In the cellular type of radiators, in which zig-zag, substantially vertical passages are formed between adjacent units, a serious objection is encountered, in that in these zig-zag passages there are always a plurality of more or less dead water pockets due to the zig-zag contour of said water passages. In a short space of time these water pockets become clogged by precipitated matter from the through-flowing water, thereby not only soon seriously impeding the effectiveness of the radiator, but in time stopping the down-flow of the water.

While in my structure I employ a modified form of zig-zag water passages, I combine with these passages a plurality of vertical water grooves repeatedly intersecting the zig-zag passages, whereby a vertical fall of water at accelerated speed is obtained. These vertical passages connect the zig-zag passages, whereby the water at high speed is caused to flow along the zig-zags and to carry with it the matter precipitated. I thus combine the advantages of the increased water cooling surface effected by the zig-zag passages with the increased

speed of flow due to vertical head, thereby maintaining the original effectiveness of the radiator for an indefinite period of time.

To more fully understand the details of my invention, I now have reference to the drawings already referred to, in which Figure 1 is a vertical section of my invention in its entirety. Fig. 2 is a plan of a fragment of a strip constituting one of the units of my invention. Fig. 3 is a plan of a fragment of a slightly modified form of strip. Fig. 4 is an edge view of the part shown in Fig. 2. Fig. 5 is a longitudinal section on line 5—5 of Fig. 2. Fig. 6 is a transverse section on line 6—6 of Fig. 4. Fig. 7 is a transverse section on line 7—7 of Fig. 5. Figs. 8 and 9 are sections of modifications of the device.

Like parts are designated by the same characters and symbols of reference in all the figures.

A, in the drawings denotes the radiator complete, and B, one of its unit blanks. Inasmuch as the several units constituting the cooling sections of the radiator are true duplicates, I will describe only one of them, and will, therefore, employ the singular number.

The unit blank B is comprised of a strip 85 of thin, sheet metal, preferably brass or copper on account of their high degree of heat conductivity. The width of this blank is equal to what is termed the width of the radiator, or in other words, the length of 90 the air passages, and its length is somewhat greater than the height of the radiator, (the length of the water passages.)

Into the face of this strip there are pressed a plurality of equally spaced, substantially 95 V-shaped, depressions 10. These depressions terminate in a flattened peak 11, and connecting adjacent successive depressions are like, flattened, portions 12, of the unit blank B. It is now to be noted that the 100 sides 13, or legs, as it were, forming the V-shaped depressions 10, are arranged on a gentle decline, so that the resultant depressions are in reality of elongated V shape.

Along the marginal edges of the blank B, 105 the depressions 10, are swaged outwardly to form projections 14, at the peaks 11. These swaged-out portions 19, gradually recede on an incline, until the same finally merge into the sides or legs 13, at the flattened portion 110 12, at the base of the depressions. In the face of the V-shaped depressions 10 are

pressed a plurality of preferably semicircular plane grooves 15, which grooves are disposed longitudinally of the unit blank B, and which merge into the sides 13 of the V-shaped depressions at a point substantially half way between adjacent depressions, all for the reasons hereinafter set forth.

The unit blank B having been provided with its proper complement of depressions, 10 is bent back upon itself, as seen in Figs. 4 and 5, with the peaks 11 pointing away from each other, and with the flattened portions 12 of the blank B in register with, and contacting, each other. The free ends of the 15 blank are then bent toward each other and overlapped, as at 16, Fig. 5, and soldered together. It is now to be observed that the point of rebending the blank in the process 20 of completion of a unit, is at the center of the flattened portion 12, so that when the rebending is accomplished, the V-shaped depressions are directly opposing each other and in register.

Attention is now called to the fact that 25 when the blank is rebent, what was initially a V-shaped depression, becomes an inverted V-shaped protuberance, and vice versa. All members 10 having the projections 14 and grooves 15, become protuberances in the final 30 analysis, the depressions in the blank being disposed between adjacent protuberances. The now completed unit thus constitutes a plurality of diamond-shaped members having parallel passages 17, and these passages 35 extend in the direction of the width of the radiator. The said passages are intermittently contracted by the walls of the grooves 15, so that a contraction of the air current is caused to take place in the passages, as 40 the said walls are passed, which air expands beyond the said walls until the next wall is encountered. I find that better results are obtained by alternately contracting and speeding the air flow and then slowing it 45 and permitting the same to expand rather than to cause the air to flow through a smooth, unobstructed passage.

In assembling a radiator, I first take two units and cause them to be nested together, 50 the projections on one unit fitting into the depressions 10 of the other unit. The projections 14 of one unit contacting with the flattened portions 12, of the other unit, causes a slight separation of the body of the 55 two units and creates a zig-zag water passage 18 between the legs or sides of the depressions or protuberances 10, as the case may be; and, attention is drawn to the fact that the faces of the receding projecting 60 portions 19 of the projections 14, contact each other for the entire length of the units. The marginal edges of these coacting receding portions 19 are dipped into a bath 65 of molten solder, thus making the joint water tight, and thereby closing the mar-

ginal edges of the zig-zag water passages against leakage.

The *modus operandi* pursued in assembling and joining together the full complement of units into a radiator section is to 70 nest these units together in an open metallic frame, similar to a printer's chase, and lock the units in proper relationship, after which the marginal edges of the entire structure are successively dipped into a molten bath 75 of solder and sweated into, for all intents and purposes, a unitary structure.

It has hereinbefore been stated that the water grooves 15 formed in the faces of the respective protuberances extend longitudinally one half of the entire distance between adjacent depressions; and it may now be pointed out that the adjacent protuberances are separated by the zig-zag water passages 18; that the respective water grooves 15 are 85 in true alinement with each other, and are a constant continuation of each other; they are interrupted and intersected by the zig-zag passages at each proturbance of the respective units, and therefore, each water 90 groove outlets into its respective portion of its coöperating zig-zag passage. By this construction, the down-flow of water is divided between the passages and the grooves. The acceleration in speed of the water in 95 the grooves, when crossing the zig-zag passages, induces an increase in speed of flow of the water in the passages, due to suction, and this increased speed results in the carrying along of matter which would otherwise 100 be precipitated upon the inclined faces of the passages, thereby, almost entirely, eliminating the clogging of the said passages.

In Fig. 3, I have disclosed a slight modification of the unit blank B, the modification 105 being characterized by an odd number of water grooves 15^a, instead of an even number as in Fig. 2. The object of this construction is clearly shown in Fig. 6, wherein the water grooves 15^a are staggered with respect 110 to the water grooves 15, so that the through-flowing air in the air passages 17, is intermittently deflected and caused to alternately impinge against the walls of the water grooves 15 and 15^a, in a manner readily comprehended.

After the units have been assembled and soldered together, the upper ends of the unit structure are soldered, brazed, or sweated into a hot water receptacle C, and the lower 120 ends likewise connected to a cooling water receptacle D, of typical construction.

In Figs. 8 and 9, I disclose modified types of construction. In Fig. 8, I indicate the termini 15^a of the water grooves 15, as being 125 rounded off, to afford a freer outlet of the grooves into the water passages 18. In Fig. 9, I indicate the said water grooves as of rectangular cross section instead of semi-circular. Such, and other changes are well 130

within the spirit of my invention, and the scope of the claims.

I have hereinbefore disclosed the preferred mode of practising my invention, but 5 I reserve the right to make such and any changes as might occur to one skilled in the art to which this invention appertains, or to make any and all such alterations as may be permitted under the doctrine of equivalents.

10 Having thus fully described my invention I claim as new, and desire to secure to myself by Letters Patent of the United States:—

1. A radistor, including a plurality of 15 duplicate units, there being zig-zag, substantially vertical, water passages between adjacent units, said units having vertical water grooves intersecting said zig-zag passages.
- 20 2. A radiator, including a plurality of duplicate units, there being zig-zag, substantially vertical, water passages between adjacent units, water grooves formed in said units, said water grooves intersecting said 25 passages, said units having a plurality of through-flowing air passages, said air passages being alternately contracted and enlarged.
- 30 3. A radiator, including a plurality of duplicate units, there being zig-zag, substantially vertical, water passages between adjacent units, said units having continu-

ously interrupted vertical water grooves intersecting said passages and outletting into the respective portions of said passages.

35

4. A radiator, including a plurality of 40 duplicate units, there being substantially vertical zig-zag water passages between adjacent units, said units having water grooves intersecting said passages, said water grooves outletting into the respective portions of said passages, said units having a plurality of through-flowing air passages, 45 said passages being intermittently contracted by the walls of said water grooves.

5. A radiator, including a plurality of 50 vertically disposed, duplicate, nested together, units, each of said units comprising a plurality of tubular protuberances, a plurality of depressed portions connecting said protuberances, projections along the marginal edges of said protuberances merging into said depressed portions; said projections of adjacent units nesting into said depressed portions, there being formed between said 55 adjacent units, by said projections, substantially vertical, zig-zag water passages, there being in adjacent faces of said protuberances vertical water grooves intersecting and outletting into said water passages.

60

In testimony that I claim the foregoing as my invention, I have hereunto set my hand.

CHARLES F. SPERY.
